US0D1018016S

(12) **United States Design Patent** (10) **Patent No.:** **US D1,018,016 S**
(45) **Date of Patent:** **** Mar. 19, 2024**

(54) **SOCKS**

(71) Applicant: **Arebesk Inc.**, Los Angeles, CA (US)

(72) Inventor: **Leana P. Shayefar**, Los Angeles, CA (US)

(73) Assignee: **Arebesk Inc.**, Los Angeles, CA (US)

(**) Term: **15 Years**

(21) Appl. No.: **29/804,116**

(22) Filed: **Aug. 18, 2021**

(51) **LOC (14) Cl.** **02-04**

(52) **U.S. Cl.**

USPC **D2/994; D2/980**

(58) **Field of Classification Search**

USPC **D2/896, 900, 902, 904, 906–908,**

D2/916–924, 925–945, 947–960,

D2/969–979, 980–994

CPC **A43B 1/00; A43B 1/02; A43B 1/04; A43B**

3/00; A43B 3/02; A43B 3/06; A43B 3/10;

A43B 3/12; A43B 3/14; A43B 5/00;

A43B 5/001; A43B 5/008; A43B 5/06;

A43B 5/10; A43B 5/12; A43B 23/00;

A43B 23/02; A43B 23/04

(57) **CLAIM**

The ornamental design for socks, as shown and described.

DESCRIPTION

FIG. 1 is a perspective view showing a first embodiment of my new socks design in use;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a perspective view showing a second embodiment of my new socks design in use;

FIG. 9 is a top view thereof;

FIG. 10 is a bottom view thereof;

FIG. 11 is a left side view thereof;

FIG. 12 is a right side view thereof;

FIG. 13 is a front view thereof; and,

FIG. 14 is a rear view thereof.

The evenly dashed broken lines depict environmental subject matter, and form no part of the claimed design. The dash-dot-dash broken lines depict the cut line and form no part of the claimed design.

1 Claim, 12 Drawing Sheets
